UNITED STATES PATENT OFFICE.

WILLIAM WENDERHOLD, OF NEW YORK, N. Y., ASSIGNOR TO CRU PATENTS CORPORATION, A CORPORATION OF NEW YORK.

SAFETY DRIVE FOR MOTION-PICTURE APPARATUS.

1,402,274.

Specification of Letters Patent.

Patented Jan. 3, 1922.

Application filed April 28, 1917. Serial No. 165,083.

To all whom it may concern:

Be it known that I, WILLIAM WENDERHOLD, a citizen of the United States, residing at New York city, in the county and State of New York, have invented certain new and useful Improvements in Safety Drives for Motion-Picture Apparatus, of which the following is a clear, full, and exact description.

This invention relates to an automatic clutch mechanism for drive shafts in motion picture apparatus and projectors and the like.

The object is to provide a clutch mechanism controlled by a film band that will disengage the motive power automatically when the film has insufficient tension or breaks, so that all film manipulating parts in such machine cease to operate instantly. The device as disclosed is chiefly designed to disengage automatically. It is also designed to enable the operator to re-connect the driving connection clutch at any time independently, but the duration of said connection is always controlled by the automatic disengaging mechanism which is controlled by the film itself.

Referring to the drawings:

Fig. 1 is a partial side elevation of a motion picture apparatus;

Fig. 2 is a partial section showing film controlled roller and support therefor;

Fig. 3 is a partial section of Fig. 1 showing the throw-out lever;

Fig. 4 is a vertical section of Fig. 1 through the main drive shaft taken on the line 4—4, Fig. 1 and looking in the direction of the arrows;

Fig. 5 is a side elevation of the clutch arm taken on the line 5—5, Fig. 4 and looking in the direction of the arrows;

Fig. 6 is a section through the clutch arm shaft;

Fig. 7 is a clutch detail showing one engaging member looking in the direction of the arrows at 7—7, Fig. 4;

Fig. 8 is a view taken on the line 8—8, Fig. 5 and looking in the direction of the arrows;

As illustrated in Fig. 1, the film F is advanced by the usual film rollers 1, 2, 3 and 4, which are mounted in the supporting structure 5. In this structure is also mounted a yieldable bracket 6 supporting in one end a roller 7 loosely mounted upon shaft 8, which shaft is extended through the bracket

6 to exert pressure upon pawl 9 in the upward direction. When the film F leaves the film roller 4, it is passed over the roller 7, thereby pressing bracket 6 downward. When, however, the tension in said film becomes slack, or if the film should break, then the spring 10 will push the bracket 6 upward again. The pawl 9 is mounted on a pivotally mounted lever 11. When members 6 and 8 move upward this lever 11 is lifted also and drops back again of its own accord, when not otherwise retarded by member 15.

Lever 11 is mounted upon shaft 12 in support 5 carrying at its other end a fixed catch 13, and a spring 14 is mounted upon shaft 12 to give the shaft and the parts thereon mounted a tension sideways. The fixed catch 13 is engaged by the pivotally mounted handle bar 15 upon shaft 16. Shaft 16 is mounted in support 5 and fastened on the upper end of this shaft is the clutch arm 17. The handle bar 15 is fastened to shaft 16 by springs 27 and 28, the clutch arm having two pins 17^a engaging a groove in the clutch 18, which clutch is slidably mounted upon the main drive shaft 19 but is connected thereto to rotate therewith. The pins 20 engage the hub of the main drive gear 21 loosely mounted on shaft 19. This hub has a series of holes (see Fig. 7).

On shaft 19 is mounted the usual crank arm 22 on one end and a gear 23 on the other end, which meshes with gear 24 upon axis 25, which carries the drive pulley 26, which is driven by motive power, when crank arm 22 is not employed. It is understood that gear 21 operates the entire apparatus.

The functions of springs 28 and 27 are as follows: When handle bar 15 is forced around shaft 16 by hand till the catch extension 15^a has passed the catch 13, the spring 28 becomes very taut and thereby exerts pressure upon clutch arm 17, which will force clutch 18 toward hub of gear 21, and engage the holes therein by means of pins 20. This spring 28 is now highly charged with tension and held that way by catch 13. If, however, the pins 20 are not directly opposite the holes in gear hub 21, then the spring 27 (which is the weaker) will allow the clutch arm 17 to lag behind the holes meet pins 20. In this way the charging of spring 28 is not interfered with. Now, should the film F allow the arm 6 and its shaft 8 to go upward, touch pawl 9 on lever

11, lever 11 and shaft 12 and catch 13 will instantly release the handle bar 15, and spring 28 being released thereby will instantly disconnect the clutch 18 with great force.

Various devices have been made to accomplish this purpose, either by electrical or mechanical arrangement, but they are not efficient, owing to the fact that the film is not strong enough to operate clutches and even if the film were made stronger, the film should not be used for that purpose, as it is too valuable to be used for mechanical functions. I have therefore designed a clutch which is charged with a spring tension by hand, and very sensitively discharged automatically by the mere absence of film. This is the chief feature of my invention.

What I claim as my invention is:

1. In a motion picture apparatus, a driving shaft, a clutch thereon, an arm operating said clutch, a spring mounted on said arm, a handle bar operating said arm against the tension of said spring, a catch adapted to engage the handle bar, a lever supporting said catch, said lever having a pawl, a shaft engaging said pawl, said shaft carrying a roller, said roller being supported by a bracket, said bracket being yieldably mounted and said roller being adapted to be influenced by the motion of a film band adjacent thereto, and a supporting structure for the entire apparatus.

2. In a motion picture apparatus, a driven shaft, a clutch thereon, means for exerting and maintaining a tension on said clutch, means for governing said clutch, said means including a pawl and a movable member adapted to engage said pawl, said member being controlled by a film passing over the same, and means whereby said member re-

leases the tension on said clutch when the influence of the film is withdrawn.

3. In a motion picture apparatus the combination of a driving member and a clutch, means for exerting tension on said clutch and normally tending to place said clutch out of engaging relation with said member, means controlled by a film in said apparatus for retaining said clutch in engagement with said driving member, and means actuated by the absence of film in said apparatus for releasing said retaining means.

4. In an apparatus of the class described, the combination of a driving member and a clutch mounted thereon, means for exerting tension on said clutch to normally tend to place the clutch out of engagement with said driving member, a detent for retaining said clutch against tension in engagement with said driving member, means controlled by a film passing through said apparatus for retaining said detent in position and means for becoming operative by the absence of the film in said apparatus for releasing said detent.

5. In a motion picture apparatus, the combination of a driving member and a clutch, of manually operated means for exerting a tension on said clutch, and for maintaining said tension on said clutch to normally cause the same to tend to disengage said driving member, means controlled by the presence of the film in said apparatus for retaining said clutch in engagement with said driving member and means controlled by the absence of the film in said apparatus for allowing said clutch to disengage.

Signed at New York city, New York, this 27th day of April, one thousand nine hundred and seventeen.

WILLIAM WENDERHOLD.
